UNITED STATES PATENT OFFICE.

DAVID GENESE, OF BALTIMORE, MARYLAND.

COVERED SUPPOSITORY AND METHOD OF MAKING SAME.

SPECIFICATION forming part of Letters Patent No. 727,344, dated May 5, 1903.

Application filed April 5, 1902. Serial No. 101,578. (No model.)

To all whom it may concern:

Be it known that I, DAVID GENESE, a citizen of the United States, residing at Baltimore, in the State of Maryland, have invented new and useful Improvements in Covered Suppositories and Methods of Making Same, of which the following is a specification.

My invention relates to covered suppositories and method of making same, and has for its object to produce in a simple and economical manner a covered suppository comprising a medicinal substance, such as solidified glycerin, inclosed and securely sealed in an air-tight manner in a removable envelop.

15 In proceeding according to my invention the glycerin or other similar substance is first molded to the desired shape to form the suppository. It is then inserted in a cone-shaped envelop of tin-foil open at its larger 20 end. Said envelop is then placed in a press or die having molds the shape and size of the molded glycerin, and the envelop is compressed firmly and smoothly about the suppository, its open end being closed thereby 25 and crimped and otherwise indented to seal such opening. To further seal the envelop and to cover or close any openings that may be therein due to imperfections in the metal,

I next subject the envelop to a bath of an oxid 30 of the metal of which it is composed, in the form, substantially, of a paste, which in the present instance would be oxid of tin, or otherwise coat the suppository with such oxid, as by painting, which by reason of its affinity for 35 the metal of the envelop will adhere thereto, covering or closing any openings and when dry forming a thin smooth air-tight coating.

In order that my invention and the manner 40 of carrying it out may be readily and clearly understood by those skilled in the art, I have illustrated the same in the accompanying drawings, in which—

Figure 1 is a perspective view of a thin metal conoidal envelop. Fig. 2 is a longitudinal section of the same. Fig. 3 is a side elevation of a molded body of glycerin or similar substance constituting the suppository. Fig. 4 is a longitudinal section of the envelop shown in Fig. 1 with the suppository inserted 50 therein. Fig. 5 shows in section the envelop containing the suppository inserted in a

press. Fig. 6 shows in section the two dies of the press brought together to compress the envelop about the suppository and to close and crimp the open end thereof. Fig. 7 is a 55 perspective view of the article as it appears when taken from the press, and Fig. 8 is a longitudinal section showing the article coated with the metallic oxid.

Referring to the drawings, 1 indicates the 60 envelop, conoidal in shape, as stated, having its lower end 2 closed, and which envelop is preferably made of tin-foil, although aluminum or other suitable metal may be employed. This envelop, except as to its larger 65 end 3, which is left open, is made as nearly imperforate as possible.

4 indicates a body of solidified glycerin or similar substance which has been molded to a cigar shape to form a suppository. This 70 shape of the glycerin body is found desirable, for the reason that its sides and butt-end will fit snugly the interior of the envelop 1, and the large end of the envelop may be readily compressed about the curved pointed end 5 75 to present a smooth surface. This shape of the glycerin body is further desirable as facilitating the insertion of the suppository in the proper organ.

6 indicates the upper and 7 the lower die 80 of a suitable press, in each of which is a mold 8 of the size and shape of one-half of the suppository 4 should the latter be bisected longitudinally. In addition the die 6 is provided just beyond the pointed end of the mold 8 85 with a transverse feather or rib 9 and other ribs 10, and the lower die 7 is correspondingly recessed, as at 11, to receive said ribs. The suppository, inclosed in the envelop 1, being placed on the lower die 7 in the mold 8 there- 90 of, as shown in Fig. 5, the upper die 6 is brought down upon or closely adjacent to said lower die, and as a result the envelop 1 will be firmly pressed about the suppository 4, and the end portion 3 of said envelop will be flattened out beyond the pointed end of the suppository, as shown in Fig. 7, the ribs 9 and 10 and the recesses 11 serving to crimp and seal the open end of the envelop, as indicated at 12, and to further indent the flattened-out portion of the envelop to "take up" the superfluous material, as indicated at 13. The metal

covered suppository is now coated in any suitable manner, as previously described, with an oxid of the metal of which the envelop is composed, such coating being indicated by 5 14 in Fig. 8 and serving, as previously described, to cover or close any imperfections or openings in the envelop.

Having thus fully described my invention, what I claim as new is—

- 10 1. The method of covering suppositories which consists in forming an envelop of a suitable metal, inserting the suppository therein, pressing the envelop about the suppository and closing the envelop, and then 15 coating the envelop with an oxid of the metal of which it is composed.
2. The herein-described article comprising a body of medicinal substance covered with

metal, said metal being coated with a metallic oxid.

3. The herein-described article comprising a suppository inclosed in a metallic envelop, said envelop being coated with an oxid of the metal of which it is composed.

4. The herein-described article comprising 25 a suppository incased in an envelop of tin-foil, said envelop being coated with an oxid of tin.

In testimony whereof I have hereunto set my hand in presence of two subscribing witnesses.

DAVID GENESE.
